L. POTEMKIN

HAIR WAVER

Filed Dec. 31, 1921

INVENTOR

Lev Potemkin.
BY *H. S.* ATTORNEY
P. P. Bourne

UNITED STATES PATENT OFFICE.

LOUIS POTEMKIN, OF BROOKLYN, NEW YORK.

HAIR WAVER.

Application filed December 31, 1921. Serial No. 526,162.

To all whom it may concern:

Be it known that I, LOUIS POTEMKIN, a citizen of Russia, and resident of New York city, borough of Brooklyn, in the county of 5 Kings and State of New York, have invented certain new and useful Improvements in Hair Wavers, of which the following is a specification.

My invention relates to improvements in 10 devices for waving or curling women's hair.

The object of my invention is to provide a simple hair waver that will have the effect to retain the hair lock or strand under compression by means of outer bars having corrugations pressing against opposite outer sides of such lock or strand to cause the latter to assume a wavy condition.

My invention comprises an inner bar around which a lock or strand of hair is to 20 be wound and two outer bars to be clamped against said hair, said outer bars having corrugations to engage the outer sides of said hair to indent it, and means to detachably connect the free ends of said outer bars 25 together.

My invention also comprises novel details of improvement that will be more fully hereinafter set forth and then pointed out in the claim.

Reference is to be had to accompanying 30 drawings, forming part hereof, wherein—

Figure 1 is a perspective view of my improved hair waver;

Fig. 2 is a side view of the waver in position of use;

Fig. 3 is an edge view of Fig. 2;

Fig. 4 is an enlarged detail sectional view, and

Fig. 5 is a section on line 5, 5, in Fig. 1.

Similar numerals of reference indicate 40 corresponding parts in the several views.

The numeral 1 indicates an inner or central bar, around which a lock or strand of hair is to be wound in an ordinary manner, 45 and at 2, 3, are outer bars on opposite sides of the inner bar to bear upon said wound hair. The bars 1, 2, 3 are shown united at one end by a rivet 4 which serves as a pivot for bar 1 between the outer bars 2, 3, the

50 opposite outer ends of which bars are normally free from one another. The bars 2, 3, are shown made in a single piece of material bent at 5. The bars 2, 3 at their free portions beyond rivet 4 have a normal outward spring tendency, being made of elastic ma-

terial, such as suitable spring metal. The bars 2, 3 are corrugated transversely so as to press into or dent the hair wound on bar 1 when clamped against the hair.

The outer ends of the bars are adapted to 60 be detachably connected together. The outer free end of bar 2 is shown bent to extend reversely over and spaced from the bar, to not interfere with the adjacent end of bar 1 but in position to cooperate with the free end of bar 3 to retain it. The bars 2 and 3 are longer than bar 1. The end 2^a of bar 2 is internally recessed or dented at 2^b in an outward direction to receive the reduced end 3^a of bar 3. Said recess 2^b opens 70 through the inner edge of end 2^a of bar 1 to receive end 3^a of bar 3 and has side webs or walls 2^c to prevent sidewise movement of bar 3, (Fig. 5).

When my improved hair waver is to be 75 used the bars 2 and 3 are separated, (Fig. 1), the bar 1 may be swung on pivot 4 to extend laterally, and a suitable lock or strand of hair is wound around bar 1, as in a spiral direction from its inner to its outer end.

The bars 2, 3, are then pressed together to bear against the opposite sides of the wound hair 6, the free ends of bars 2, 3 being locked together, due to their outward spring tendency, Fig. 3. The bars 2, 3 have sufficient 85 flexibility to permit their free ends to be moved sideways to permit insertion of end 3^a to recess 2^b to retain the bars locked, and to permit the reverse operation to release the bars. When the bars are clamped upon the 90 hair on bar 1, the corrugations of the bars 2, 3 press against the hair forcibly, being resisted by the inner bar 1, whereby the hair is dented from the exterior. By retaining the hair clamped between the corrugated bars for a sufficient time the hair will be given a so-called wavy appearance or condition, the resiliency of the bars serving to retain them snugly against the hair. The waver may be removed from the hair by pushing bar 1 95 with the attached hair sideways from between the bars 2, 3, and then removing bar 1 from the hair, without requiring to separate bars 2 and 3.

While I have shown an inner bar 1 and two outer corrugated bars the waver may have a single outer corrugated bar which will cooperate with the inner bar to retain them locked in the manner described respecting bars 2 and 3.

Having now described my invention, what I claim is:—

A hair waver comprising opposing bars secured together at corresponding ends and extending divergently therefrom, one of said bars having a return end portion extending over said bar, said end portion having an inner recess opening through the edge of said end portion, and provided with side webs, the corresponding end of the other bar

being reduced to fit in said recess between said webs, said bars having an outward spring tendency to retain said reduced end in said recess, and a third bar pivoted between the first-named ends of the other bars. ¹⁵

Signed at New York city, in the county of New York, and State of New York, this 30th day of December, A. D. 1921.

LOUIS POTEMKIN.
